Primary Examiner — Cathron C Brooks*Assistant Examiner* — Sharon S Oum(74) *Attorney, Agent, or Firm* — McGarry Bair PC(57) **CLAIM**

The ornamental design for a ceiling fan, as shown and described.

DESCRIPTION

FIG. 1 is a top perspective view of a ceiling fan, showing our new design;

FIG. 2 is a bottom perspective view of the ceiling fan of FIG. 1;

FIG. 3 is a top view of the ceiling fan of FIG. 1;

FIG. 4 is a bottom view of the ceiling fan of FIG. 1;

FIG. 5 is a front view of the ceiling fan of FIG. 1, with the rear view being identical thereto; and,

FIG. 6 is a right side view of the ceiling fan of FIG. 1, with the left side view being identical thereto.

Portions of the ceiling fan that are shown in broken lines form no part of the claimed design. The ceiling fan blades are shown with a symbolic break in their length. The appearance of any portion of the ceiling fan blade between the break lines forms no part of the claimed design.
